UNITED STATES PATENT OFFICE.

LEO S. CHADWICK, OF EAST CLEVELAND, OHIO, ASSIGNEE TO THE CLEVELAND
STOVE COMPANY, OF CLEVELAND, OHIO, A CORPORATION OF OHIO.

STOVE.

1,140,874.

Specification of Letters Patent. Patented May 25, 1915.

Original application filed July 23, 1914, Serial No. 852,611. Divided and this application filed March 4, 1915. Serial No. 11,985.

To all whom it may concern:

Be it known that I, Leo S. Chadwick, a citizen of the United States, residing at East Cleveland, in the county of Cuyahoga and State of Ohio, have invented a certain new and useful Improvement in Stoves, of which the following is a full, clear, and exact description, reference being had to the accompanying drawings.

10 This invention relates to liquid fuel stoves of the type shown in my co-pending application No. 852,611, filed July 23, 1914, whereof this application is a division.

The invention which forms the subject 15 matter of this application, has for its general object the provision of a stove of the aforesaid character having means whereby the liquid fuel supply may be replenished at any time in a particularly convenient manner and without the necessity and annoyance of soiling the hands, and without waste of time.

A further object of the invention is to 20 provide a novel construction whereby the foregoing desired results may be conveniently, efficiently, and economically attained.

I accomplish the foregoing objects in and 25 through the construction illustrated in the accompanying drawings which form a part

30 hereof, wherein—

Figure 1 represents a front elevation of a stove having any liquid fuel supply means incorporated therein; Fig. 2 is an enlarged sectional detail taken through the front of 35 the compartment from which the liquid fuel is distributed to the burners, and shows the carrier and the dispensing receptacle in operative relation to the distributing receptacle; Fig. 3 is a view, similar to Fig. 2, 40 showing the carrier in its outward or inoperative position, with a dispensing receptacle therein; Fig. 4 is a horizontal sectional view corresponding to the line 4—4 of Fig. 2; Fig. 5 is a similar view on the line 5—5 45 of Fig. 3; Fig. 6 is an enlarged sectional detail through the bottom of the liquid fuel distributing receptacle and adjacent portions of the dispensing receptacle and drain sink; and Fig. 7 is a perspective view of a dispensing receptacle.

Describing by reference characters the various parts illustrated herein, 1 denotes generally the base of a liquid fuel stove. In the space above this base and below the top

plate 2 and the oven 3, three compartments 55 A, B and C are provided. These compartments may be conveniently formed between end panels 4 and 5, back plates 6 and 7, a transverse partition 8, and an angular plate comprising a transverse portion 9 and a 60 front portion 10. The compartment A is provided beneath the oven and between the panel 4 and the angular portions 9 and 10 of the plate last referred to; the compartment B is provided between the transverse 65 portion 9 of the last mentioned plate, the transverse partition 8, and the back plate 7, the oven 3 extending above the tops of the compartments A and B and forming a 70 cover therefor. The compartment C is conveniently formed beneath the top plate 2 and between the partition 8 and the end panel 5. The front plate 10 of the compartment A extends preferably the entire distance between the top of the base 1 and the 75 bottom of the oven 3, being of the same height as the panel 4 and the partition 9 to which it is connected and of which it preferably forms a part. The front plate 10 is provided with an opening therein, the 80 metal surrounding said opening being preferably flanged inwardly, as shown at 10°, for the purpose of strength.

In the lower portion of the compartment B there is located the liquid fuel distributing receptacle 11, said receptacle being shown as a cylindrical cup supported by a tubular or cylindrical standard 12, carried by the base 1. The upper end of this distributing receptacle 11 is surrounded by a 85 drain sink, which may be conveniently supported on top of the standard 12 and which flares upwardly and outwardly from the lower part of the distributing receptacle. This sink indicated generally at 13, is preferably rectangular in plan and is provided with vertical side walls 14 extending from the upper ends of the flared bottom walls 15 therebeneath. The front bottom wall 16 of the sink extends through the opening in the 90 front plate 10 and is provided at its outer or front end with an upwardly projecting wall 17, which is shorter than the side walls 14. The rear wall 18 of this sink is provided with an upwardly and outwardly 95 curved splash apron 19. The forward portions of the side walls 14 of the sink are reinforced by plates 20. Firmly secured to

said walls, and within these plates and the adjacent portions of the side walls, there is supported a hinge pintle 21. As will be apparent, particularly from Figs. 2 to 5 inclusive, the forward end of the drain sink projects through an opening in the front plate 10, which opening extends through the upper end of the plate and is of substantially the same width as the sink. In order that the lower portion of the plate 10 may serve as a firm support for the front end of the sink, said plate is flanged outwardly (as indicated at 10^b) directly beneath the overhanging portion of the sink and may be secured to such portion of the sink, as by means of solder.

A closure for the opening in the front plate is afforded by the sheet metal door 22, the same being preferably beaded about its edges, as shown at 22^a, and having a central vertical slot 23 therein, for a purpose to be explained hereinafter. The lower edge of the door is bent outwardly at right angles to its body portion and is provided with a sleeve 24 by which the door is hinged upon the pintle 21.

Carried by the inner surface of the door 22 is an open-ended, box-like carrier, for the liquid fuel dispensing receptacle, such box-like carrier comprising side walls 25, 26 an end wall 27, the remaining end wall being formed by the door 22. For convenience of description, the carrier will be assumed to be in the position shown in Fig. 3 in which position it is adapted to receive a dispensing receptacle prior to the application of the same to the distributing receptacle and the drain sink; and the terms "front," "back," "top," and "bottom" will be correspondingly applied to the parts of the carrier. The side walls 25, 26 are extended below the bottom 28 of the carrier, as shown at 29, and these side wall extensions provide means for pivotally supporting an operating handle for the carrier. This operating handle, indicated at 30, is carried by a pair of arms 31, which are pivotally connected at their inner ends to the extensions 29, as indicated at 32. The arms 31 are connected by a transverse rod 33 which, when the carrier is in the position shown in Fig. 3, is adapted to be received within notches 34 and which, when the door 22 is closed and the carrier thereby caused to assume the position shown in Fig. 5, is adapted to be received within the notches 35 in the extensions 29. By means of the handle 30, the door and the carrier are swung upon the hinge pintle 21 to the position shown in Fig. 2, the handle 30 swinging through an arc of substantially 180°,—until the transverse rod 34 rests in the notches 35. The corner of each wall extension 29, adjacent to the notch 34 therein, is flared outwardly, as indicated at 36 (see Figs. 2, 3 and 5) whereby the out-

turned portions of said wall extensions are adapted to bear against the arms 31 and, by their resilience, yieldingly support the handle in the position shown in Fig. 3, where it can be conveniently reached for the purpose of swinging the dispensing receptacle into operative relation to the distributing receptacle. 70

37 denotes a metal strip which may be secured in any convenient manner to the horizontally extending portion 22^b of the door, which metal strip overhangs the edge of the door and forms a supporting ledge for the bottom edge 38 of the liquid dispensing receptacle 39. It will be observed that the portion of the ledge which overhangs the receptacle 39 forms an acute angle with the body of the door 22 whereby, when the carrier and the door is swung to the position shown in Fig. 2, a channel 37^a is provided at 80 the bottom of the closed door. 85

The liquid dispensing receptacle is indicated at 39 and consists of a metallic can, which is adapted to be inserted, in inverted position, and to fit loosely within the carrier and is provided with a neck 40 which is internally threaded for the reception of a threaded cap 41. Secured to this cap is a perforated cylindrical guide 42. Mounted within the cap and the guide is a valve stem 43 having a valve 44 thereon co-operating with a valve seat 45 in the cap and adapted to close the port 46 through said seat. A spring 47, interposed between the valve body and the end of the cylindrical guide is adapted to hold the valve to its seat. Secured to the same end of the receptacle 39 as the valve is a handle 47, said handle being offset a slight distance from the center of the receptacle. Within what will be the front wall of the dispensing receptacle (when the latter is in the position shown in Fig. 2) is a vertical recess 48. This recess is narrow and relatively deep and extends substantially the full length of the receptacle 39. 105 This recess forms a receptacle and a guard for a liquid level gage, said gage consisting of a glass tube 49 having metal caps 50 at the ends thereof through which it is connected to the ends of the recess 48 and thereby to the interior of the dispensing receptacle. The arrangement is such that the recess 48 will be in alignment with the slot 23 in the door, whereby the gage may be observed through said slot when the door is 110 closed. 115

When it is desired to replenish the fuel supply, the condition of such supply being indicated by the gage 49, the operator swings the door 22 and the carrier 39 to the position shown in Fig. 3. The dispensing receptacle may now be removed from the carrier by the use of any approved form of lifter, the use of such a device being desirable in order to protect the hands of the operator from be- 120 125

coming soiled by contact with the receptacle, especially if the refilling operation should have to take place during the process of cooking or baking. Because of the fact that the receptacle 39 fits loosely within the carrier and that the handle 47 is offset from its center, the lifting of the receptacle will cause it to tilt sufficiently to enable the corner adjacent the ledge 37 to clear such ledge and 10 permit the easy removal of the receptacle. A filled receptacle may then be substituted for the one removed and, because of its angle of inclination, due to the location of the handle as aforesaid, may be inserted in the 15 carrier without the necessity of touching the same. When the receptacle rests upon the then bottom wall 28 of the carrier, it assumes an upright or vertical position, as shown in Fig. 3, with its upper rear corner 20 beneath the ledge 37. As the operator swings the door 22 and the carrier upwardly toward and into the position shown in Fig. 2, the receptacle moves by gravity toward the door, bringing the flange 38 into 25 the channel 37^a, while the corner diagonally opposite the ledge 37 will bear against the wall 26 in such position as to project the neck 40 of the dispensing receptacle into the upper end of the distributing receptacle 11. 30 Should it happen that, during this swinging operation, the flange 38 should not enter the channel 37^a, the opposite edge of the dispensing receptacle will contact with the splash apron 19 and the receptacle thereby 35 be forced toward the door a sufficient distance to cause the flange to enter such channel.

While the parts may be so proportioned as to cause the dispensing receptacle to rest 40 upon and be wholly supported by the ledge 37, I prefer that the upper edge of the distributing receptacle 11 be at a higher elevation than said ledge, when the parts are in the position shown in Fig. 2, so that the 45 dispensing receptacle will rest securely upon the distributing receptacle.

It will be noted that the supply pipe 51, which conducts liquid fuel from the dispensing receptacle 11 to the various burners, communicates with the bottom of said receptacle at one side of the center thereof, as indicated at 52. This leaves the central portion of the bottom of the receptacle 11 intact and in position to be impinged upon by the end of the 55 valve stem 43, before the dispensing receptacle contacts with the upper edge of the distributing receptacle, whereby the valve 44 is lifted from its seat 45, permitting liquid fuel to flow from the receptacle 39 into the receptacle 11 until the level in the latter receptacle reaches the mouth of the neck 40 and seals the same against further discharge of liquid from the dispensing receptacle until such discharge is permitted by the lowering 60 of the liquid level in the receptacle 11

to a point which will break the seal. Upon the removal of the neck 40 from the receptacle 11, as the carrier is swung outwardly to the position shown in Fig. 3, a quantity of liquid will naturally adhere to such neck 70 and either be thrown away from the dispensing receptacle by the centrifugal action induced by a rapid swinging movement of the carrier or be dropped from the neck upon the upper surface of the 75 said receptacle if the swinging movement be a slow one. Any liquid that may be thrown away from the dispensing receptacle by the centrifugal action referred to will be intercepted by the apron 19 and 80 returned thereby into the sink, by the employment of a sink having a draining surface of greater area than the cross sectional area of the carrier and arranged as shown in the drawing, it will be evident that any 85 liquid which may accumulate on the dispensing receptacle and any liquid which may be within the carrier will, when the carrier is in the position shown in Fig. 2 be delivered through the sink and the opening 90 11^a, into the distributing receptacle.

Having thus described my invention, what I claim is:—

1. A device of the character set forth comprising, in combination, a wall having 95 an opening, a liquid distributing receptacle adjacent said wall, a drain sink discharging into said receptacle and having one portion of its draining surface projecting through the opening in the wall and another portion 100 thereof projecting in the opposite direction from the distributing receptacle, a splash apron inclined upwardly and away from the last mentioned portion of the sink, a carrier hinged on a horizontal axis above 105 the portion of the drain sink that projects through the said opening, and a liquid dispensing receptacle supported by the carrier, said dispensing receptacle having a discharge opening and being supported by 110 said carrier in a manner that will cause the discharge opening of the dispensing receptacle to be presented in operative relation to the distributing receptacle when the carrier is swung above the latter receptacle. 115

2. A device of the character set forth comprising, in combination, a wall having an opening, a liquid distributing receptacle adjacent said wall, a substantially rectangular drain sink discharging into said receptacle and having substantially vertical side walls, one end of said sink extending through the opening in the front wall of the compartment, a splash apron extending upwardly and away from the opposite end of 120 the sink, an open ended carrier hinged on a substantially horizontal axis to the portions of the side walls of the sink which project through the opening in the wall, a ledge overhanging one side of the open end 125 130

- of said carrier in proximity to the hinge axis, means whereby the carrier may be swung upon the aforesaid axis, and a liquid dispensing receptacle supported within the carrier in a position to present its discharge opening in operative relation to the distributing receptacle and with a portion of the dispensing receptacle resting upon the aforesaid ledge, when the door is closed.
- 10 3. A device of the character set forth comprising a liquid distributing receptacle, an open-ended carrier pivoted on a horizontal axis adjacent to said receptacle and adapted to be swung to a vertical position above or below said receptacle, a ledge overhanging the wall of the carrier adjacent to the hinge axis when the carrier is in its lowered position, and a liquid dispensing receptacle constructed and adapted to be supported within the carrier, with the ledge overhanging a wall thereof and having a discharge outlet adapted to be brought into operative relation with the distributing receptacle when the carrier is swung thereabove.
- 15 4. A device of the character set forth comprising, a liquid distributing receptacle, an open-ended carrier pivoted on a horizontal axis adjacent to said receptacle and adapted to be swung to a vertical position above and below said receptacle, said carrier having a ledge arranged to overhang the wall which is adjacent to said hinge axis with a portion of said ledge projecting downwardly within said wall when the carrier is in its lowered position, a liquid dispensing receptacle constructed and adapted to be received within the carrier below the downwardly projected portion of the ledge and between the same and the hinged wall of the carrier and having a discharge outlet arranged to coöperate with the distributing receptacle when the carrier is swung above the latter.
- 20 5. A device of the character described comprising, in combination, a distributing receptacle, an open-ended carrier, having one wall thereof pivoted on a horizontal axis adjacent to said receptacle, a ledge carried by the pivotally supported wall and having a portion that is inclined downwardly and inwardly from the top of said wall when the carrier is in position to receive a dispensing receptacle, a liquid dispensing receptacle constructed and adapted to be inserted within the carrier with a wall thereof beneath and overhung by the inclined portion of the ledge, the latter receptacle having a discharge outlet coöperating with the dispensing receptacle, and means on the opposite side of the distributing receptacle from the axis and adapted to engage the dispensing receptacle, thereby to maintain the wall thereof which is adjacent to the hinged wall of the carrier within the channel formed between said wall and the inclined portion of the ledge.
- 25 6. In a device of the character set forth, the combination of a distributing receptacle, a dispensing receptacle having a mouth and supporting edge, a carrier for the dispensing receptacle which is hinged with respect to the first mentioned receptacle and adapted to be swung above the same, a ledge on the carrier which the supporting edge of the dispensing receptacle engages during the swinging of the carrier, and means for preventing the disengagement of said edge from the ledge during the swinging operation.
- 30 7. In a device of the character described, the combination of a distributing receptacle, a carrier for a dispensing receptacle hinged adjacent to the first mentioned receptacle and adapted to be swung above the same, and a handle pivoted to the carrier and adapted to be moved with respect thereto as the carrier is swung upon the hinge.
- 35 8. In a device of the character described, the combination of a distributing receptacle, a carrier for a dispensing receptacle hinged adjacent to the first mentioned receptacle and adapted to be swung above the same, and a handle pivoted to the carrier and capable of an angular movement with respect thereto substantially equal to the angular movement of the carrier with respect to the first mentioned receptacle.
- 40 9. In a device of the character described, the combination of a distributing receptacle, a carrier for a dispensing receptacle hinged adjacent to the first mentioned receptacle and adapted to be swung above the same, a handle pivoted to the carrier and adapted to be moved with respect thereto as the carrier is swung above the distributing receptacle, and stops limiting the angular movement of the handle.
- 45 10. In a device of the character described, the combination of a distributing receptacle, a carrier for a dispensing receptacle hinged adjacent to the first mentioned receptacle and adapted to be swung above the same, a handle pivoted to the carrier and adapted to be moved with respect thereto as the carrier is swung upon the hinge, stops limiting the angular movement of the handle, and means for retaining the handle at one end of its movement.
- 50 11. In a device of the character described, the combination of a distributing receptacle, a carrier for a dispensing receptacle hinged adjacent to the first mentioned receptacle and adapted to be swung above the same, a handle pivoted to the carrier and adapted to be moved with respect thereto as the carrier is swung upon the hinge, and means for retaining the handle at one end of its movement.
- 55 12. In a device of the character set forth,

the combination of a distributing receptacle, a carrier for a dispensing receptacle hinged adjacent the first mentioned receptacle upon a substantially horizontal axis and adapted to be inverted above the distributing receptacle, and a handle pivoted to the carrier upon an axis substantially parallel to the axis of the hinge and adapted to be moved with respect to the carrier as the carrier is swung upon the hinge.

13. In a device of the character set forth, the combination of a distributing receptacle, a carrier for a dispensing receptacle which is hinged at one of its ends adjacent the first mentioned receptacle upon a substantially horizontal axis and adapted to be inverted above the distributing receptacle, a handle pivoted to the other end of the carrier upon an axis substantially parallel to the axis of the hinge and adapted to be moved with respect to the carrier as the carrier is swung upon the hinge.

14. In a device of the character described, the combination of a distributing receptacle, a carrier for a dispensing receptacle hinged upon a substantially horizontal axis adjacent to the first mentioned receptacle and adapted to be inverted thereover, a handle pivoted to the carrier upon an axis substantially parallel to the axis of the hinge, stops for limiting the angular movement of the handle with respect to the carrier, and yielding means for holding the handle at one end of its movement.

15. In a device of the character described, the combination of a distributing receptacle, a carrier for a dispensing receptacle hinged upon a substantially horizontal axis adjacent to the first mentioned receptacle and adapted to be inverted thereover, a handle

pivoted to the carrier upon an axis substantially parallel to the axis of the hinge, and stops for limiting the angular movement of the handle with respect to the carrier.

16. In a device of the character described, the combination of a distributing receptacle, a carrier for a dispensing receptacle hinged upon a substantially horizontal axis adjacent the first mentioned receptacle and having side walls, a bail the ends of which are pivoted to the side walls of the carrier on an axis substantially parallel to the axis of the hinge, and an abutment carried by the bail and adapted to coöperate with portions of the side walls to limit the angular movement of the bail, the side walls having portions which project into the path of the bail and retain the bail at substantially one end of its movement.

17. In a device of the character described, the combination of a distributing receptacle, a carrier for a dispensing receptacle hinged upon a substantially horizontal axis adjacent the first mentioned receptacle and having side walls, a bail the ends of which are pivoted to the side walls of the carrier on an axis substantially parallel to the axis of the hinge, and a cross rod connecting the sides of the bail and adapted to coöperate with notches in the side walls, located on either side of the bail pivot, thereby to limit the angular limit of the bail as the carrier swings upon its axis.

In testimony whereof, I hereunto affix my signature in the presence of two witnesses.
